FURNITURE CONSTRUCTION

Forest Wilson, Chicago, Ill. (P.O. Box 6, Medinah, Ill.)

Filed May 5, 1958, Ser. No. 733,118

6 Claims. (Cl. 155—197)

The present invention relates to furniture and more particularly to a constructional brace for use in furniture.

Because of the many advantages of a wooden frame construction over a metal frame construction for furniture, it has been, and still is, the usual practice to utilize wood for the constructional framing members of furniture, and in high quality furniture, the various rails, braces, and other parts of the frame are preferably glued and doweled together. Obviously, the labor cost of constructing furniture of this nature is quite high and it would be desirable to provide a frame construction which while having the advantages of a wooden frame could be more easily assembled so as to reduce the labor cost of manufacturing the frame and, moreover, which would reduce the actual cost of the material used in the frame.

Therefore, an object of the present invention is to provide a new and improved frame construction for use in furniture.

Another object of the present invention is to provide a new and improved wooden furniture construction utilizing a metal brace member which may be assembled to the wooden members of the frame by ordinary screws.

A further object of the present invention is to provide a new and improved metallic brace member for use in furniture construction.

Briefly, the above and further objects are realized in accordance with the present invention by providing a metallic brace member which may be used as a spreader rail between oppositely disposed rails in a wooden frame, the latter rails being interconnected by means of a spring or the like which is maintained under tension by the rails between which the spreader rail is positioned. Moreover, in order to enable the use of this same brace for other purposes thereby to increase its versatility and reduce the number of items which must be stocked by a furniture manufacturer, the brace is constructed so that it may replace the usual corner blocks, and moreover, includes supporting means for vertical or divergent furniture legs.

The invention, both as to its organization and method of operation, together with further objects and advantages thereof, will best be understood by reference to the following detailed description taken in connection with the accompanying drawing, in which:

Fig. 1 is a fragmentary perspective view of the frame construction for a sofa showing a brace embodying the present invention replacing conventional corner blocks;

Fig. 2 is a somewhat enlarged sectional view of the frame of Fig. 1 taken along the line 2—2 thereof;

Fig. 3 is a fragmentary sectional view taken along the line 3—3 of Fig. 2;

Fig. 4 is a somewhat enlarged sectional view taken along the line 4—4 of Fig. 1.

Referring now to the drawings and particularly to Fig. 1 thereof, there is shown a portion of the rectangular frame of a furniture piece 10, the frame comprising as its principal members a pair of front and back rails 11 and 12 and end rails 13, only one of the end rails being shown but it being understood that a similar end rail is provided

at the other ends of the front and back rails 11 and 12. The members 11, 12, and 13 are preferably doweled and glued together and a plurality of generally sinusoidal cushion spring 14 of the non-sag type are stretched between the rails 11 and 12 and suitably connected thereto. The springs 14 are maintained under tension at all times by the frame and thus exert an inward force on the rails 11 and 12 which in the absence of a spreader rail or the like connected between the rails 11 and 12 intermediate the ends thereof would cause the front and rear rails to bow inwardly and thus detract from the overall appearance of the furniture. Inasmuch as the springs 14 during actual use of the furniture bow downwardly due to the weight of an object, such as a person being positioned thereon, the spreader rails which must be provided between the rails 11 and 12 to prevent bowing thereof, should be sufficiently low so as not to obstruct the natural movement of the springs 14. However, such spreader rails should engage the front and rear rails at a substantial distance from the bottoms thereof. Consequently, the upper surfaces of the spreader rails should be concave, and in accordance with prior art practice where the spreader rails are made of wood, it is desirable that they be convex at the bottom so as to provide a spreader rail which is sufficiently thick at all points therealong to prevent breaking. These prior art spreader rails have necessarily been made on band saws and are quite expensive. Moreover, in order for them to remain intact throughout long periods of use, it is necessary that they be doweled and glued to the frame and because of the doweling they must necessarily be built into the frame at the time that the frame is initially fabricated.

Also, in order to prevent flexing of the frame 10 it has been necessary in accordance with prior art techniques to employ triangularly shaped corner blocks which are glued into the corners formed by the rails 12 and 11 with the end rails 13 and these corner blocks include suitable means such as drilled holes therein for receiving the legs upon which the furniture is mounted. In accordance with present-day practice, furniture is shipped without legs and, therefore, it is necessary to provide means on the furniture whereby the legs may be assembled just prior to the use of the furniture.

In accordance with the present invention, there is provided a brace 16 which may be used as the spreader rail in wooden frame furniture and which may also be used to replace the conventional corner blocks and leg supports. Since a single brace member 16 may be used for all of these purposes the number of pieces which must be stocked by a furniture manufacturer are reduced, thus reducing his inventory. Moreover, the brace 16 better performs the functions of either a spreader rail or of a pair of corner blocks than do the prior art type spreader rails and prior art type corner block themselves.

Considering the brace 16 in detail, and also referring to Figs. 2, 3, and 4, the rail 16 is generally channel shaped having a bottom web 17 and a pair of upstanding side flanges 18 and 19 which are disposed in substantially parallel relationship. The web 17 is provided with reversely bent portions 21 near the opposite ends thereof and each of these reversely bent portions includes an intermediate portion 23 which is disposed between the adjacent end portion 24 of the web and the intermediate portion 25. The end portions 24 and the intermediate portion 25 are mutually parallel and the intermediate portions 23 intersect these parallel portions at obtuse angles which, as shown in the drawing, may be approximately 155 degrees. This particular angle is, of course, determined by the width of the furniture and as may be seen later by the angle at which it is desired to mount the legs with respect to the frame of the furniture.

In order to strengthen the central portion of the brace

16, a longitudinally extending rib 26 is disposed in the center of the web 17 and extends longitudinally of the brace 16 between the intermediate portions 23. The portions of the flanges 18 and 19 which are disposed along the intermediate portion 25 of the web 17 are relatively narrow but from the locations of the intermediate portion 25 to the end of these flanges they become progressively wider so as to provide, in the case of flange 19, a substantially high upstanding portion 28 at each end thereof. The flange 18 has similar wider portions at the ends thereof. The end of the upstanding portion 28 is turned inwardly to provide a lip 29 which lies in a plane substantially perpendicular to the principal longitudinal axis of the brace 16. As best shown in Figs. 1, 2, and 4, the end portions 24 of the web extend beyond the ends of the flanges 18 and 19 and include slightly upturned sides 30 and 31 which provide strengthening members. It will be apparent from the drawing that the upturned sides 30 and 31 are in effect extensions of flanges 18 and 19. The extending ends of the brace 16 fit below the bottom edges of the front and rear rails 11 and 12 and the lips 29 as well as the ends 34 of the flange 18 abut against the inner faces of the rails 11 and 12. When the brace 16 is used as a spreader rail, one or more of them are positioned intermediate the ends of the rails 11 and 12 and are secured to the rails 11 and 12 by suitable screws 35 which extend through openings in the bottom of the web 17 near the ends thereof. Since the upstanding portions 28 of the flange 19 engage the rails 11 and 12 throughout a substantial portion of their height, no bowing of the rails can take place due to the pull exerted thereon by the springs 14. Moreover, because of the generally concave upper surface of the brace 16, as best shown in Fig. 4 of the drawing, no interference with the normal operation of the spring 14 is encountered.

In order to enable the mounting of legs in the brace 16, a hole 37 is pressed in and tapped in the end portions 24. Moreover, in order to enable the use of the brace 16 where divergent type legs are to be employed, another set of holes 38 are pressed and tapped in the angulated intermediate portions 23 of the web 17.

In order to enable the use of the brace 16 to replace a pair of conventional corner blocks, and as best shown in Fig. 1, each upstanding portion 28 is provided with a set of holes 40 and 41 to accommodate headed screws which extend through these holes and are used to fasten the brace 16 to the end rail 13. A screwdriver hole 42 may also be provided in the flange 18 opposite the hole 41 to facilitate the threading of the screws through the hole 41. It should be understood that the brace 16 may be used at any intermediate portion of the frame as well.

From the above description it will be readily seen by those skilled in the art that the braces 16 may be added to a frame after it has been doweled and glued, thus reducing the time required to fabricate the frame. Moreover, a single type of brace 16, which is adapted to be stamped out from a metal sheet and thus may be manufactured at a relatively low cost, may be used for a number of purposes such, for example, as a spreader rail or to replace a pair of conventional corner blocks.

While a particular embodiment of the invention has been shown, it will be understood, of course, that it is not desired that the invention be limited thereto since modifications may be made, and it is, therefore, contemplated by the appended claims to cover any such modifications as fall within the true spirit and scope of the invention.

Having thus described the invention, what is claimed as new and desired to be secured by Letters Patent of the United States is:

1. A furniture brace comprising an elongated metallic channel having a web and a pair of parallel side

flanges, a reverse bend in said web near one end of said channel, a reverse bend, identical to the first of said bends, near the other end of said channel, a centrally disposed, axial rib in said web extending from one of said reverse bends to the other, the end portions of one of said flanges being substantially higher than the center portion, the longitudinal ends of said one of said flanges being inturned to provide a re-entrant lip at each end lying in a plane which is perpendicular to the principal longitudinal axis of said channel, said one flange having at least one hole in each of the higher end portions thereof, said web having a hole in each of the intermediate portions of said reverse bends, said web further having a hole in each of the end portions thereof, and said web extending beyond said lips and having upturned side edges continuing from the plane of said lips to the ends of said brace.

2. A furniture brace as set forth in claim 1 wherein said reverse bends each comprise an intermediate portion which interconnects two mutually parallel portions of said web and meets said portions at an obtuse angle.

3. In a piece of furniture, a rectangular wooden frame, including at least a pair of oppositely disposed side rails and an end rail, a metallic brace interconnected between said oppositely disposed side rails, spring means interconnected between said side rails and maintained in tension by said frame, said brace being of channel construction, having a web and side flanges, the end portions of at least one of the side flanges of said brace being substantially higher than the portion of said flange disposed near the longitudinal center of said brace, the end of said one side flange abutting the inner side of the end rail, and said web extending beneath said side rails and being secured thereto by suitable fastening means.

4. In a piece of furniture, a rectangular wooden frame including at least a pair of oppositely disposed side rails and an end rail, a metallic brace interconnected between said oppositely disposed side rails, said brace being of channel construction having a web and side flanges, one of said side flanges being juxtaposed with said end rail connected between said oppositely disposed side rails, means connecting the ends of said brace to said respectively adjoining side rails, and means connecting said one flange to said end rail, said last mentioned means being disposed in proximity to the respective corners formed by said oppositely disposed side rails and said end rail.

5. The combination set forth in claim 4 wherein said web extends beneath said oppositely disposed side rails and is provided with leg supporting holes in proximity to said oppositely disposed side rails.

6. A brace for connection between oppositely disposed rails in a piece of furniture, comprising an elongated member having first and second reverse bends near the ends thereof so as to provide said member with a generally concave central portion, said member having an upstanding side flange, said flange being substantially wider near the ends of said member, and said flange terminating a substantial distance from the ends of said member, the ends of said upstanding side flange including an inturned lip disposed at right angles to the longitudinal axis of said side flange.
